Fred A. Thaheld, Minden, Nev., assignor to Evert
Wilkerson, Fairfield, Calif.

Continuation-in-part of design application Ser. No.
12,684, July 10, 1968. This application Feb. 3,
1969, Ser. No. 15,612

Term of patent 7 years

Int. Cl. D15—08

U.S. Cl. D92—15

FIG. 1 is a front elevational view of a portable hand-tufting machine showing my new design;

FIG. 2 is a side elevational view thereof;

FIG. 3 is a rear elevational view thereof; and

FIG. 4 is a side elevational view of the side opposite of that shown in FIG. 2.

This is a continuation-in-part of my co-pending application, Ser. No. D-12684 filed July 10, 1968 and now abandoned.

I claim:

The ornamental design for portable hand-tufting machine, substantially as shown.
